(57) **CLAIM**

The ornamental design for a training device, as shown and described.

DESCRIPTION

FIG. 1 is a front perspective view of a training device; FIG. 2 is a rear view thereof; FIG. 3 is a top perspective view thereof; and, FIG. 4 is a bottom perspective view thereof and reveals aspects of the design that are not visible in the other figures. The broken lines in the above-described figures depict environmental subject matter and form no part of the presently claimed design.

1 Claim, 4 Drawing Sheets
